UNITED STATES PATENT OFFICE.

IRA SHAFFER, OF AFTON, IOWA.

TWINE-CUTTER.

SPECIFICATION forming part of Letters Patent No. 703,484, dated July 1, 1902.

Application filed April 28, 1902. Serial No. 105,101. (No model.)

To all whom it may concern:

Be it known that I, IRA SHAFFER, a citizen of the United States, residing at Afton, in the county of Union and State of Iowa, have invented certain new and useful Improvements in Twine-Cutters; and I do declare the following to be a full, clear, and exact description of the invention, such as will enable others skilled in the art to which it applies to make and use the same.

The invention relates to twine-cutters.

The object of the invention is to provide a device of this character which shall be simple of construction, durable in use, comparatively inexpensive of production, efficient in action, and by means of which any given amount of twine after being unrolled from the ball may be expeditiously severed and then leave projected from the cutter a piece of the twine to be grasped when it is again desired to unwind from the ball.

With this and other objects in view the invention consists of certain novel features of construction, combination, and arrangement of parts, which will be hereinafter more fully described, and particularly pointed out in the appended claims.

In the accompanying drawings, Figure 1 is a perspective view showing my improved twine-cutter in its normal position. Fig. 2 is a similar view showing the twine-cutter in the act of severing the twine. Fig. 3 is a rear view of a fragment of the base of the twine-cutter; and Fig. 4 is a longitudinal vertical sectional view through the base and the hinged arm, taken on the line of passage of the twine through the base, hinged arm, and cutter-head.

Referring to the drawings, 1 denotes the base, which is provided with a twine-opening 2.

4 denotes a semicircular recess, the base 5 of which is arranged in a horizontal plane.

6 denotes two lugs, and 7 denotes an angular arm pivoted between said lugs and having a tubular portion 8 and provided with a cutter-head 9, which has an aperture 10, communicating with the tubular portion.

11 denotes a cutter-blade pivoted to the cutter-head at 12 and adapted with its edge to cross the aperture 10 and sever the twine.

A spring 13 is employed to exert its energy

to force the blade away from the aperture 10 and against the stop 14.

16 denotes a crank-shaft journaled in bearings 17. One end of the crank-shaft is connected by a chain or other flexible connection 18 to an extended end of the blade, and the other end of the crank-shaft is connected by a chain or other flexible connection 19 to the base, so that when the free end of the arm 8 is swung downwardly the sag in the chain 19 will be taken up and said chain stretched, whereby the shaft 16 will be rocked and will, through its chain connection 18 with the blade, cause the blade to traverse the aperture 10 and sever the twine.

20 denotes two stiff coil-springs connected to the base and to the free end of the arm 8 and are designed to restore the arm from the position shown in Fig. 2 to that shown in Fig. 1, and when the arm is drawn backward by these springs it will strike a buffer 21, secured to the base.

22 denotes a tension device which consists of a plate 23, pivoted at one end, as shown at 24, to the back of the base and having its outer end projecting forwardly and connected to a spring 25, the lower end of which is secured to a pin or staple 26, projecting from the edge of the base. This plate is provided with a stop-slip 27, which bears upon the flat base 5 of the semicircular recess 4 and exerts a pressure upon the twine as it is being drawn through the aperture 28 of said plate.

29 denotes an expandable and compressible guide preferably in the form of a guide-spring, one end of which is secured to the base and the other end of which is secured to the arm 8 and registers with the tubular portion thereof. This guide is adapted to bridge the space formed between the arm and the base when said arm is swung from the position shown in Fig. 1 to that shown in Fig. 2, so that when the arm moves to its normal position, or from the position shown in Fig. 2 to the position shown in Fig. 1, the twine will not be cut between the inner end of the arm and the base.

The end of the twine is threaded through the aperture 2, up through the hole in the tension device, and then through the coil-spring and tubular portion of the swinging

arm and through the cutter-head. When it is desired to sever a piece of twine, the projecting end of the twine is grasped and pulled in the direction of the arrow shown in Fig. 1 5 until the desired amount has been unwound from the ball. Now by pulling downwardly upon the twine the swinging arm will be swung from the position shown in Fig. 1 to that shown in Fig. 2, thus tightening the 10 chain 19, causing it to rock the shaft 16, and forcing the knife across the aperture 10 in the cutting-head. The twine is thus severed, and in the upward movement of the swinging arm the blade will be withdrawn from 15 across the aperture in the cutter-head, and the end of the twine within the tubular portion of the arm is projected through the opening in the cutter-head to enable it to be grasped when it is desired to be again unwound from the ball. In order to limit the 20 downward movement of the swinging arm, I provide a stop-chain 30, one end of which is connected to the swinging arm and the other to the base-plate. This chain is of such 25 length that when it becomes taut the knife will traverse the aperture 10.

From the foregoing description, taken in connection with the accompanying drawings, the construction, mode of operation, and advantages of the invention will be readily understood without requiring an extended explanation.

Various changes in the form, proportion, and details of construction may be made 35 within the scope of the invention without departing from the spirit or sacrificing any of the advantages thereof.

Having thus described my invention, what I claim, and desire to secure by Letters Patent, is—

1. In a twine-cutter, the combination with a suitable base and a twine-tension device, of an angular arm hinged to the base and provided with a tubular portion through which 45 the twine is adapted to pass, a knife pivoted to the outer end of the arm, a connection between the knife and the base-plate whereby when said arm is swung downwardly the knife will be actuated to sever the twine, and an 50 expandible and compressible guide extending from the tension device to the tubular portion of the arm and adapted to bridge the space between said arm and the base when the arm is swung downwardly, substantially as set forth.

2. In a twine-cutter, the combination with a suitable base and a twine-tension device, of an angular spring-actuated arm hinged to the base and provided with a tubular portion through which the twine is adapted to pass, 60 a knife pivoted to the outer end of the arm, a connection between the knife and the base-plate whereby when said arm is swung downwardly the knife will be actuated to sever the twine, and an expandible and compressible 65 guide extending from the tension device to the tubular portion of the arm and adapted to bridge the space between said arm and the base when the arm is swung downwardly, substantially as set forth.

3. In a twine-cutter, the combination with a suitable base and a twine-tension device, of an angular spring-actuated arm hinged to the base and provided with a tubular portion through which the twine is adapted to pass, 70 means for limiting the downward movement of said arm, a knife pivoted to the outer end of the arm, a connection between the knife and the base-plate whereby when said arm is swung downwardly the knife will be actuated to sever the twine, and an expandible and compressible guide extending from the tension device to the tubular portion of the arm and adapted to bridge the space between said 75 arm and the base when the arm is swung downwardly, substantially as set forth.

4. In a twine-cutter, the combination with a suitable base having an opening, of a tension device consisting of an apertured plate hinged to the base and having a lip projecting from the base of the opening, a spring for exerting pressure upon the plate to hold the lip against the base of the opening, an angular spring-actuated arm hinged to the base and provided with a tubular portion through 90 which the twine is adapted to pass and with a cutter-head having an opening through which the end of the twine is adapted to project, a spring-actuated knife pivoted to said head, and a connection between said knife and the base whereby when said arm is swung downwardly the knife will traverse the opening in said head, substantially as set forth.

In testimony whereof I have hereunto set my hand in presence of two subscribing witnesses.

IRA SHAFER.
